(57) **CLAIM**

The ornamental design for an ergonomic palm support, as shown and described.

DESCRIPTION

FIG. 1 is a front right top perspective view of an ergonomic palm support in an operating configuration.

FIG. 2 is a rear right bottom perspective view of the ergonomic palm support of FIG. 1.

FIG. 3 is a top view of the ergonomic palm support of FIG. 1.

FIG. 4 is a bottom view of the ergonomic palm support of FIG. 1.

FIG. 5 is a left side view of the ergonomic palm support of FIG. 1.

FIG. 6 is a right side view of the ergonomic palm support of FIG. 1.

FIG. 7 is a front view of the ergonomic palm support of FIG. 1.

FIG. 8 is a rear view of the ergonomic palm support of FIG. 1.

FIG. 9 is a rear right top perspective view of the ergonomic palm support of FIG. 1 in a folded configuration; and, FIG. 10 is a front right bottom perspective view of the ergonomic palm support of FIG. 1 in the folded configuration.

The features shown in broken lines are portions of the ergonomic palm support that form no part of the claimed design.

1 Claim, 10 Drawing Sheets
